ATTORNEYS

UNITED STATES PATENT OFFICE.

MAX ARM, OF NEW YORK, N. Y.

LOCK.

Application filed January 19, 1922. Serial No. 530,395.

To all whom it may concern:

Be it known that I, MAX ARM, a citizen of the United States, and a resident of the city of New York, borough of Manhattan, in 5 the county and State of New York, have invented a new and Improved Lock, of which the following is a full, clear, and exact description.

This invention relates to a lock, and has 10 for an object the provision of a lock in which the operation is extremely simple but in which the engagement of the lock with the corresponding member on the door jamb is extremely effective.

15 Another object resides in the provision of means whereby the lock may operate either by a knob or by a key.

A further object resides in the provision of means whereby whenever the knob is used 20 to actuate the lock bolt the connection between the bolt and the key-operating means may be removed.

A still further object resides in the provision of a lock bolt of particular construction 25 whereby a double engagement between the casing on the jamb and the casing on the door is effected.

Another object resides in the particular construction of parts whereby the assembly 30 of this lock and its placement on a door is made in a very simple manner by reason of the construction.

A further object resides in the particular construction and arrangement of parts 35 which are hereinafter described and claimed and shown in the accompanying drawings.

The invention is illustrated in the drawings, of which—

Figure 1 is a vertical section taken on the 40 line 1—1 of Fig. 3, showing the parts in the retracted position.

Fig. 2 is a similar view showing the parts in their actuated positions.

Fig. 3 is a horizontal section taken on the 45 line 3—3 of Fig. 2.

The form of the invention shown in the drawings is a preferred form, although it is understood that modifications in the construction and arrangement of the parts and 50 in the character of the materials used may be adopted without departing from the spirit of the invention.

The invention is applicable to a door jamb 1 and a door 2. The door 2 is provided 55 with the usual lock aperture 3 in which a lock casing 4 is disposed. This casing is

fastened into the aperture 3 in the usual manner by a projection or pin 6 from the rear face of the lock and the engagement thereof with a plate 5 on the inner face of the door. 60 A projecting member 7 extends inwardly from the rear end of the lock casing and is adapted when the key is inserted in the lock to be actuated through the intermediary of the key barrel. The remainder of the 65 mechanism is contained within a lock casing 8 disposed against the inner face of the door adjacent the jamb 1. This casing cooperates with a similar casing 9 disposed on the jamb. The abutting faces of these two casings are 70 provided with transversely extending plates 10 and 11 between which and the upper and lower walls of these casings are formed apertures 12, 13, 14 and 15 through which the lock plate 18 extends to lock the casing 8 75 to the casing 9. This lock plate 18 is in the form of a curved arm connected to a plate 17 pivoted at 16 for rotation within the casing 8. This plate 17 is curved and provided along its edge with spaced slots 19, 20, 80 21 and 22. The slot 22 is provided at one edge with an overhanging shoulder or flange 23. With these various slots in the edge of the plate 17 pins 24, 25 and 26 are adapted to engage. These pins are mounted on 85 the face of a rotatable plate 27. This plate is disposed in a recess 28 formed in a contact plate 29 of the casing 8. This contact plate is formed with an integral projecting pin or post 30 which forms a pivot pin for 90 the plate 17 carrying the curved lock plate 18. This plate 18 is provided, preferably, with a triangularly-shaped aperture 31 through which a similarly-shaped stem 32 extends. This stem has a reduced portion 33 to which 95 a knob 34 is connected. A shoulder 35 is formed on the stem 32 and between this shoulder and the casing 8 a spring 36 extends, tending normally to hold the stem 32 inwardly in engagement with the projecting member 7 extending from the key-operated block 4. This member 7 extends into a bore 37 formed in the end of the stem 32.

The normal retracted position of the parts 105 is shown in Fig. 1. The movement of the key will cause the projecting member to turn in the stem 32 and by this rotation of the stem the plate 27 is turned. This turning will move the pin 24 into engagement with 110 the slot 20 when moved in the direction indicated by the arrow in the figure. This

causes the lock plate 18 to extend through the apertures 14 and 12 down through the casing 9 and then back through the apertures 13 and 15. For the full actuation of the lock plate 18 it requires the engagement of the pins 26 and 25, respectively, with the slots 21 and 22.

In the position shown in Fig. 2, the plate has been extended to its full actuated position and the pin 25 is in engagement with the shoulder or flange 23 at the outer end of the slot 22. It will be apparent that further movement of the pin and the plate 27 is impossible by reason of the interposition of this flange 23. Therefore, it will be apparent that the lock plate can be moved only so far and no farther. Movement of the plate 27 in the opposite direction from that shown in Fig. 2, of course, withdraws the bolt within the casing 8.

If it is desired to actuate the plate 18 by reason of the turning of the knob 34 without turning the projecting member 7 related with the key lock 4, then it is merely necessary to pull on the knob 34 and withdraw the end of the stem 32 from engagement with the projecting member 7. This withdrawal is sufficient to cause the disengagement above mentioned but not sufficient to withdraw the stem from engagement with the plate 27.

It will be apparent, therefore, that my construction is simple, economically manufactured, easy to assemble and correspond-

ingly easy to repair; that the parts are few in number, strong and rugged in their construction and arrangement, and by having the curved lock plate it will be noted that the plate extends across the gap between the casings 8 and 9 at two points, thus effecting a double locking action.

What I claim is:

1. A lock mechanism which comprises a rotatable locking plate having a plurality of slots in its periphery, a rotatable actuating plate, pins on the actuating plate to sectionally engage in the slots in the first plate to move said plate, a knob stem engaging the second plate, and means permitting said knob to be slid axially with respect to said plate.

2. A lock mechanism which comprises a rotatable locking plate having a plurality of slots in its periphery, a rotatable actuating plate, pins on the actuating plate to sectionally engage in the slots in the first plate to move said plate, a knob stem engaging the second plate, means permitting said knob to be slid axially with respect to said plate, a key-operated lock, and a projecting stem on the key-operated lock normally engaging with the knob stem but being disengaged therefrom when the knob stem is slid axially as above mentioned, whereby the second mentioned plate can be actuated by the knob alone when desired.

MAX ARM.
